A. Z. Vencill ATTORNEY.

UNITED STATES PATENT OFFICE.

LEMUEL F. HOWARD, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

INDICATION MEANS FOR LIGHT SIGNALS.

Application filed March 2, 1921. Serial No. 449,144.

To all whom it may concern:

Be it known that I, LEMUEL F. HOWARD, a citizen of the United States, residing at Edgewood Borough, in the county of Allegheny and State of Pennsylvania, have invented certain new and useful Improvements in Indication Means for Light Signals, of which the following is a specification.

My invention relates to signals of the type comprising lamps, and has for an object the provision of means for indicating illumination of the lamp at a point remote from the lamp.

Apparatus embodying my invention is particularly well adapted for use in connection with railway signals which are controlled by the levers of interlocking machines. In systems of this character the lever is usually provided with a lock which is known as an "indication device." One feature of my invention is the provision of means for controlling this lock in accordance with the light which is actually emitted by one of the lamps in the signal governed by such lever.

I will describe several forms of apparatus embodying my invention, and will then point out the novel features thereof in claims.

In the accompanying drawings, Fig. 1 is diagrammatic view showing one form of apparatus embodying my invention, the lever lock being controlled directly by a light responsive cell which is exposed to the light from one of the signal lamps. Fig. 2 is a view showing a modification of the apparatus shown in Fig. 1, the lever lock in this instance being controlled by a relay which in turn is governed by the light responsive cell. Fig. 3 is a diagrammatic view showing the application of the Wheatstone bridge principle to apparatus embodying my invention. Fig. 4 is a diagrammatic view showing one manner in which the potentiometer principle may be applied to apparatus embodying my invention.

Similar reference characters refer to similar parts in each of the several views.

Referring first to Fig. 1, the reference character S designates a signal comprising two electric lamps G and R which lamps when illuminated are adapted to indicate "proceed" and "stop," respectively. These

lamps are at times supplied with current from the secondary 2 of a transformer T, 55 and the supply of this current is controlled by a manually operable lever A. The primary 6 of the transformer T is constantly supplied with alternating current from a suitable source which is not shown in the 60 drawing.

The supply of current to the signal lamps G and R is controlled by a contact 4 which is attached to lever A, and which engages with a contact 5^G or with a contact 5^R, according as the lever is in one position or another. As shown in the drawing, the lever A is in the right hand extreme position wherein contact 4-5^G is closed. Lamp G is then supplied with current through a circuit which passes from the right hand terminal of transformer secondary 2, through wire 7, contact 4-5^G, wire 8, lamp G, and wires 9, 10 and 11 to transformer secondary 2. When the lever A is shifted to the left, 70 the stop lamp R becomes illuminated by virtue of a circuit which passes from transformer secondary 2, through wire 7, contact 4-5^R, wire 12, lamp R and wires 13, 10 and 11 to secondary 2. 80

The lever A will usually be one of a plurality of similar levers in an interlocking machine, and, as is well understood, in apparatus of this nature the various levers are usually inter-controlled by what is known as "mechanical locking." For this reason it is desirable that a complete movement of the lever A to its extreme left hand position should be prevented until an indication is given at the lever that the stop lamp R has become illuminated. To accomplish this the lever is provided with a lock or indication device B comprising a shoulder 15 on the lever, a dog 14 normally in position to engage with this shoulder, and a magnet 16 arranged when energized to lift the dog 14 out of the path of the shoulder 15. The parts are so proportioned that when the lever is shifted to the left the shoulder 15 engages the dog 14 after contact 4-5^R 90 is closed, and that this contact remains closed after the movement of the lever has been completed to the extreme left hand position.

The magnet 16 of the lever lock B is controlled by a light responsive cell F, which

is exposed to the light emitted by the stop lamp R. The cell F has the characteristic that its electrical resistance varies in accordance with changes in the intensity of the 5 light to which it is exposed. A cell having this characteristic may be made, for example, of selenium, stibnite, or copper oxide, or may be what is known as a photoelectric cell, in which the active material 10 is an alkali metal. The precise nature of this cell and the substance of which it is composed, form no part of my present invention. The only essential feature of construction is that this cell shall be so located 15 as to receive light from the lamp R but not from any other source.

The light responsive cell F is connected in series with the magnet 16 and the secondary 3 of transformer T, the circuit being 20 from the right hand terminal of this secondary through wire 19, magnet 16, wire 18, cell F, and wire 17 to the secondary 3. The parts of this circuit are so adjusted and proportioned that when the lamp R is dark, 25 so that the resistance of cell F is comparatively high, the current supplied to magnet 16 is not sufficient to cause this magnet to lift the dog 14 out of the path of shoulder 15. When lamp R becomes illuminated, 30 however, so that the resistance of the light responsive cell F is decreased, the current which is then supplied to magnet 16 is sufficient to elevate the dog 14, so that the movement of lever A to its left hand extreme 35 position may be completed.

If desired, a visual indicator may be provided at the lever A to show the operator whether the lamp G or the lamp R of signal S is illuminated. This indicator, as here 40 shown, comprises two incandescent lamps G' and R', which are supplied with current from the transformer secondary 2, through a contact 21 which is operated by the armature of magnet 16. When signal lamp G 45 is illuminated, the contact 21 is in its lowest position, so that current is supplied to indicator lamp G' through wires 7 and 20, contact 21, lamp G' and wires 22 and 11 to transformer secondary 2. When signal 50 lamp R becomes illuminated, the consequent elevation of the armature of magnet 16 raises contact 21 to its highest position wherein the indicator lamp R' becomes energized through a circuit which will be obvious from the drawing.

Referring now to Fig. 2, the apparatus shown herein is similar to that shown in Fig. 1, except that the magnet 16 of the lever lock B is controlled by a relay Q, 60 which in turn is governed by the light responsive device F.

The relay Q comprises two windings 23 and 24. The winding 24 is constantly connected across transformer secondary 3, the 65 circuit being from this secondary through

wires 25, 31, 36 and 26, winding 24, wires 27, 28, 29 and 30 to secondary 3. Winding 23 of relay Q is also connected with secondary 3, but the circuit for this winding includes the light responsive device F. 70 This circuit is from secondary 3, through wires 25, 31 and 33, light responsive cell F, wire 34, relay winding 23, and wires 28, 29 and 30 to secondary 3. Relay Q and the circuits associated with its windings are so 75 designed and proportioned that when the cell F is dark, contact 37 is open, but that when the cell F is exposed to light rays from the lamp R this contact 37 is closed. As is well understood, the relay Q may be 80 so designed that the greater part of the energy required for operating this relay is furnished by the winding 24 and that winding 23 need supply only a comparatively small amount of controlling energy. It 85 follows that the light responsive cell F need carry only a comparatively small amount of current, and that this current can be considerably weaker than the current which must be transmitted through the cell F in 90 Fig. 1.

Magnet 16 is controlled by contact 37 of relay Q, the circuit for this magnet being from transformer secondary 3, through wires 25, 31 and 36, contact 37, wire 38, magnet 16 and wires 39 and 30 to secondary 3. 95

The operation of the apparatus shown in Fig. 2 will be apparent from the foregoing without further explanation. If desired, a visual indicator may be provided at the 100 lever A, and as here shown, this indicator comprises two lamps, G' and R'. These lamps are controlled by an additional contact 21, operated by relay Q. The circuit for these lamps is from transformer secondary 3, through wires 25, and 41, lamp G' or R', contact 21, and wires 42, 29 and 30 to secondary 3. It will be apparent that indicator lamp G' will be illuminated when signal lamp G is illuminated, and that, similarly, the indicator lamp R' will be illuminated when the signal lamp R is illuminated. 110

Referring now to Fig. 3, I have here shown diagrammatically one way in which the Wheatstone bridge principle may be applied to the apparatus shown in Figs. 1 and 2. The light responsive cell F is included in one arm of the bridge and is balanced by a fixed resistance 40 in the other arm. The connecting member of the bridge includes 120 the magnet winding 16 of Fig. 1 or the relay winding 23 of Fig. 2 in place of the galvanometer which is generally used in connection with the Wheatstone bridge network of circuits. In this form of my invention 125 the parts of the apparatus may be so adjusted that when the cell F is dark there is no current supplied to the winding 16 or 23. When the cell F is illuminated, however, the electromotive forces are unbalanced, so that 130

current then flows in winding 16 or 23. As is well understood, the apparatus may be designed that a comparatively small change in resistance of the cell F will cause a comparatively large amount of current to flow through the magnet winding 16 or the relay winding 23.

Referring now to Fig. 4, I have here shown one manner in which the potentiometer principle may be applied to the apparatus shown in Figs. 1 and 2. In this structure a resistance 43 is connected across the terminals of secondary 2 of transformer T. The light responsive device F is included in circuit with transformer secondary 3, and with the magnet 16 or the relay winding 23 according as the scheme is applied to the apparatus shown in Fig. 1 or Fig. 2. One terminal of this circuit is connected with one terminal of secondary 2, whereas the other terminal of the circuit is connected with such a point on resistance 43 that when the cell F is dark, no current flows in winding 16 or 23. When cell F is exposed to light, however, due to the illumination of the stop lamp R, the resistance of the circuit including this cell is lowered so that current of considerable amplitude flows through winding 16 or 23.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. In combination, a railway signal comprising a lamp, a lever of an interlocking machine, means controlled by a partial movement of said lever for causing said lamp to become illuminated, a lock for preventing completion of the movement of said lever, and means responsive to the light emitted by said lamp for releasing said lock.

2. In combination, a railway signal comprising a lamp, a lever of an interlocking machine, means controlled by a partial movement of said lever for causing said lamp to become illuminated, a lock for preventing completion of the movement of said lever, a cell exposed to the light emitted by said lamp and having the characteristic that its electrical resistance varies with changes in the intensity of light, and means controlled by said cell for releasing said lock when said lamp is illuminated.

3. A combination, a railway signal comprising a lamp, a lever of an interlocking machine, means controlled by a partial movement of said lever for causing said lamp to become illuminated, a lock for preventing completion of the movement of said lever, a cell exposed to the light emitted

by said lamp and having the characteristic that its electrical resistance varies with changes in the intensity of light, and a circuit including said cell and a source of current for controlling said lock.

4. In combination, a railway signal comprising a lamp, a lever of an interlocking machine, means controlled by a partial movement of said lever for causing said lamp to become illuminated, a lock for preventing completion of the movement of said lever, a cell exposed to the light emitted by said lamp and having the characteristic that its electrical resistance varies with changes in the intensity of light, a magnet for releasing said lock, and a circuit including said cell and said magnet and a source of current.

5. In combination, a railway signal comprising a lamp, a lever for controlling the illumination of said lamp, and means including a cell responsive to the light emitted by said lamp for governing said lever.

6. In combination, a railway signal comprising a lamp, a lever for controlling the illumination of said lamp, a lock for governing said lever, and means including a cell responsive to the light emitted by said lamp for controlling said lock.

7. In combination, a signal comprising a lamp, means for indicating illumination of said lamp at a point remote from the lamp, and a cell responsive to the light emitted by the lamp for controlling said indicating means.

8. In combination, a signal comprising a lamp, a cell exposed to the light emitted by said lamp and having the characteristic of varying in electrical resistance with changes in the intensity of light to which it is exposed, and means controlled by said cell for indicating illumination of said lamp at a point remote from the lamp.

9. In combination, a signal comprising a lamp, a cell exposed to the light emitted by said lamp and having an electrical resistance of one value when the lamp is illuminated and another value when the lamp is extinguished, and means controlled by the resistance of said cell for indicating illumination of said lamp at a point remote from the lamp.

10. In combination, a signal comprising a lamp, and means for indicating illumination of said lamp at a remote point comprising a cell responsive to the light emitted by the lamp.

11. In combination, a signal comprising a lamp, and means for indicating illumination of said lamp at a remote point comprising a cell exposed to the light emitted by said lamp and having the characteristic of varying in electric resistance with variations in the intensity of the light to which it is exposed.

12. In combination, a signal comprising

a lamp, a cell exposed to the light emitted by said lamp and having the characteristic of varying in electrical resistance with variations in the intensity of light to which it is exposed, a circuit including said cell and a source of current, and indicating means controlled by said circuit.

13. In combination, a railway signal comprising a lamp, a lever for controlling the illumination of said lamp, a cell responsive to the light emitted by said lamp, a lock for governing said lever, a relay controlling said lock and having two windings, a circuit for one winding including said cell and a source

of current, and means for supplying the other winding with current.

14. In combination, a signal comprising a lamp, a cell responsive to the light emitted by said lamp, a relay having two co-acting windings, a circuit for one winding including said cell and a source of current, a circuit for the other relay winding including a source of current, and means controlled by said relay for indicating illumination of said lamp at a point remote from the lamp.

In testimony whereof I affix my signature.

LEMUEL F. HOWARD.
